Richard Leier

UNITED STATES PATENT OFFICE.

SILVIO JOBIN, OF MONTREAL, QUEBEC, CANADA.

DESIGN FOR A STATUETTE.

61,138.

Specification for Design. Patented June 27, 1922.

Application filed April 21, 1921. Serial No. 463,407. Term of patent 3½ years.

To all whom it may concern:

Be it known that I, SILVIO JOBIN, a subject of the Kingdom of Great Britain, residing at Montreal, in the Province of Quebec, Dominion of Canada, have invented a new, original, and ornamental Design for a Statuette, of which the following is a specification, reference being had to the accompanying drawing, forming part thereof.

I claim:

The ornamental design for a statuette, as shown.

SILVIO JOBIN.
